1698

UNITED STATES PATENT OFFICE.

JENNIE SHEILS, OF NEW YORK, N. Y., ASSIGNOR TO THE BUTTERICK PUBLISHING COMPANY; (LIMITED,) OF SAME PLACE.

DESIGN FOR A WALKING-SKIRT.

SPECIFICATION forming part of Design No. 17,695, dated September 6, 1887.

Application filed August 8, 1887. Serial No. 246,404. Term of patent 3½ years.

To all whom it may concern:

Be it known that I, JENNIE SHEILS, of the city, county, and State of New York, have invented and produced a new and original Design for a Pattern of a Lady's Walking-Skirt; and I do hereby declare that the engraved prints accompanying this specification convey to any one accustomed to using paper patterns a clear understanding of how a garment made up by the pattern will appear.

The design shows a round walking-skirt displaying a deep drapery falling in a point to the edge at the right side and exhibiting plaits all across its top, a deep drapery falling in a point nearly to the edge at the left side

and exhibiting plaits in its back edge close to the top and in the top near its front edge, and a pull-back drapery falling to the edge at the center, where it displays straight folds, and exhibiting a shorter length at each side and 20 bournous loops falling from the belt.

What I claim as my invention, and desire to secure by Letters Patent, is—

The design for a lady's walking-skirt, as shown in the engraved print accompanying 25 this specification.

JENNIE SHEILS.
